CLAIM

The ornamental design for a hose coupling with water stop,
as shown and described.

DESCRIPTION

FIG. 1 is a front perspective view of a hose coupling with
water stop showing my new design;

FIG. 2 is a side elevation thereof;

FIG. 3 is a side elevation thereof rotated 90 from FIG. 2;

FIG. 4 is a bottom plan of FIG. 2; and,

FIG. 5 is a top plan of FIG. 2.

The broken lines showing the inside structures of the
coupling are for illustrative purposes only and form no part of
the claimed design.
